UNITED STATES PATENT OFFICE

2,520,225

BRASSIÈRE

Helen Scott-Elliott, Woodland, Calif.

Application August 28, 1948, Serial No. 46,625

3 Claims. (Cl. 2—42)

1

This invention is directed to, and it is an object to provide, a brassière of novel design.

Another object of this invention is to provide a brassière having an excellent fit; the brassière assuring of a maximum of breast support in a natural, healthful, position, minimizing strain on the glands and permitting the latter to function normally.

A further object of the invention is to provide a brassière which is arranged so that it readily compensates for body movements, while at the same time maintaining the desired support of the breasts; the design of the brassière being such that the straps, edge portions, or other parts of the garment, do not cut in, bind, or chafe.

An additional object of the invention is to provide a brassière, which is adjustable with respect to the fit of the breast receiving cups or pockets; such adjustment being accomplished by a novel arrangement of tie ribbons extending between the cups above adjustably lapping lower corner portions thereof.

It is also an object of the invention to provide a brassière, wherein its excellent fit is due in part to the provision of elastic ribbon which extends in gathered hems or casings about the edges of the breast receiving cups or pockets, whereby the latter conform to bust size. Additionally, elastic shoulder and body straps impart an upward, and lateral or sidewise tension, respectively, on the cups to further enhance the fit of the garment.

Another object of the invention is to provide a brassière which is comfortable, and easy to wear.

A further object of the invention is to produce a practical and attractive garment, and yet one which will be exceedingly effective for the purpose for which it is designed.

These objects are accomplished in the manner as will fully appear by a perusal of the following specification and claims.

In the drawings:

Fig. 1 is a perspective view, from the front, showing the novel brassière as in use.

Fig. 2 is a similar view, but shows the side and back portions of the brassière.

Fig. 3 is an enlarged front elevation of the brassière.

Fig. 4 is an enlarged sectional plan on line 4—4 of Fig. 3.

Referring now more particularly to the characters of reference on the drawings, the novel brassière comprises a pair of breast receiving cups or pockets 1, each of generally triangular configuration but rounded on opposite side edges

2

and elongated somewhat toward each other, whereby adjacent lower corner portions 2 of the cups lap each other, as shown.

The lapping, adjacent lower corner portions 2 of the cups 1 are secured together at the lower edge, and the brassière includes, at said edge, and for its full width, a continuous bottom hem or edge casing 3 formed with said cups and connecting the same against lateral separation.

10 This continuous bottom hem or edge casing 3 is gathered, as at 4, and a length of elastic 5 extends through the bottom hem or edge casing 3, being secured to the lower outside corners 6 of the cups 1. Similarly, each cup 1 is formed, about its side edges and across the top, with another and continuous hem or edge casing 7 having a length of elastic 8 extending therein between the lower corners of the cup, being secured at said latter points.

20 The hem or edge casing 7 is gathered, as at 9, in the same manner as the gathering 4 of the bottom hem or edge casing 3.

The cups 1 are of any suitable material, preferably bias cut, and formed, at the top or adjacent the apex, with a box pleat 10. Additionally, each cup includes a central dart 11 which extends upwardly from the bottom hem or edge casing 3.

A pair of tie ribbons 12 are connected to the adjacent edges of the cups 1 slightly above the lapping adjacent lower corner portions 2; such tie ribbons 12 being adapted to be secured as a bow tie 13 when the garment is in use; such tie being for the purpose hereinafter described.

35 Elastic body straps 14 are secured to the lower outside corners 6 of the cups 1 and extend rearwardly; being adapted for adjustable connection at their free ends by means of a hook 15 on one strap and a row of eyes 16 on the other strap.

40 Elastic shoulder straps 17 are secured to the cups 1 at the apex thereof, as at 18, and extend upwardly and thence downwardly to connection, as at 19, with the elastic body straps 14 intermediate their ends.

45 Normally somewhat slack, non-elastic limit tapes 20 are connected between the lower outside corners of the cups 1 and the connection points 19 on the elastic body straps 14; said limit tapes 20 overlying said body straps 14.

50 In use, the garment is worn as illustrated in Figs. 1 and 2, with the tie ribbons 12 secured together under some tension as a bow tie 13. This tying of the ribbons 12 draws all slack from the cups 1 to enhance the fit thereof. The fit of the cups 1 is further improved by the provision

of the elastic 5 and 8 in the bottom hem or edge 3, and other hem or edge casing 7 about the remaining edges of the cups, respectively. The gatherings 4 and 9 permit of the cups conforming nicely to the figure under the influence of the elastics, which elastics are under some tension when the garment is worn. The elastic body straps 14 exert lateral tension on the cups 1 from the lower outside corners, and the elastic shoulder straps 17 exert a constant lift on the cups 1 from the top; all whereby the brassière, when in use, supports the breasts in a very natural, healthful position.

The brassière is very comfortable and easy to wear; the arrangement of the elastics 5 and 8, together with the elastic body straps 14 and elastic shoulder straps 17, permitting the garment to conform with respect to body movements. There is no cutting in, binding, or chafing by the parts of the garment.

From the foregoing description it will be readily seen that there has been produced such a garment as substantially fulfills the objects of the invention as set forth herein.

While this specification sets forth in detail the present and preferred construction of the garment, still in practice such deviations from such detail may be resorted to as do not form a departure from the spirit of the invention, as defined by the appended claims.

Having thus described the invention, the following is claimed as new and useful, and upon which Letters Patent are desired:

1. A brassière comprising a pair of breast receiving cups including lapping, adjacent lower corner portions, body straps secured to the cups at their outer side edges, means to connect the body straps together adjacent their initially free ends, a shoulder strap connected between each cup at the top thereof and to one of the body straps intermediate its ends, a continuous bottom edge hem on the brassière formed with and connecting the cups against lateral separation, an elastic in the bottom hem, the ends of the elastic being secured to the ends of said bottom hem, another continuous hem on each cup about the remaining edges thereof, a separate elastic in each of said other hems, the ends of each of said separate elastics being secured to the ends of the hem in which it is disposed, and an adjustable tie connected between adjacent edges of the cups above said lapping adjacent lower corner portions.

2. A brassière comprising a pair of breast receiving cups including lapping, adjacent lower

corner portions, body straps secured to the cups at their outer side edges, means to connect the body straps together adjacent their initially free ends, a shoulder strap connected between each cup at the top thereof and to one of the body straps intermediate its ends, a continuous bottom edge hem on the brassière formed with and connecting the cups against lateral separation, an elastic in the bottom hem, the ends of the elastic being secured to the ends of said bottom hem, another continuous hem on each cup about the remaining edges thereof, a separate elastic in each of said other hems, the ends of each of said separate elastics being secured to the ends of the hem in which it is disposed, and an adjustable tie connected between adjacent edges of the cups above said lapping adjacent corner portions; all of said hems being gathered.

3. A brassière comprising a pair of breast receiving cups including lapping, adjacent lower corner portions, body straps secured to the cups at their outer side edges, means to connect the body straps together adjacent their initially free ends, a shoulder strap connected between each cup at the top thereof and to one of the body straps intermediate its ends, a continuous bottom edge hem on the brassière formed with and connecting the cups against lateral separation, an elastic in the bottom hem, the ends of the elastic being secured to the ends of said bottom hem, another continuous hem on each cup about the remaining edges thereof, a separate elastic in each of said other hems, the ends of each of said separate elastics being secured to the ends of the hem in which it is disposed, and an adjustable tie connected between adjacent edges of the cups above said lapping adjacent corner portions; all of said hems being gathered, and the body and shoulder straps being elastic.
